ABSTRACT: A flexible, nonexpansible metal watchband in which each of the tube ends on the band carries a single, centrally located tab on the underside thereof for engaging the underside of the watchcase when the band tends to drop vertically downwardly under the influence of gravity as the case is held face up, thus to limit the movement of the band to a position at which sharp corners on the band do not extend above the case.

TAB STOP FOR WATCHBAND TUBE END

BACKGROUND OF THE INVENTION

There are known in the prior art flexible and semiflexible, nonexpansible metal watchbands formed as chains or as chainlike structures. The ends of the band may be cut to conform to the shape of the case and spring pin receiving tube ends are soldered or otherwise secured to the underside of the band adjacent the ends thereof. Alternatively, decorative fittings or adapters carrying the tube ends are attached to terminal links of the band.

Whichever of the two methods described above for attaching the band to the watchcase is employed, the structure so far described embodies an undesirable characteristic. In use of bands of this type with the watch held face up, portions of the band adjacent the case hang straight down. This characteristic of the band is undesirable for a number of reasons. First, this disposition of the band makes it relatively inconvenient to slip over the wrist. Secondly, and perhaps more important, in this condition of the band sharp corners thereof adjacent the case extend above the case to positions at which the possibility exists that a person handling the band may scratch or cut himself. Obviously, also, with the band so disposed, it loses its attractive appearance.

At least one attempt has been made in the prior art to overcome the problems outlined above. Either the tube ends of the band or the decorative adapters at the band ends are formed with pairs of small laterally extending ears adapted to engage the undersides of the spring pin receiving lugs on the watchcase. This construction, however, has not proved satisfactory. In use of the band, the ears have a tendency to bend and even to break off with the result that the purpose intended to be served thereby is not accomplished. The construction of tube ends or adapters of the type described is relatively difficult and consequently is expensive. The proposed arrangement is not adapted to structures of various widths. Thus, special structures must be made for the respective widths of bands to which it is to be applied. Owing to the location of the ears, the band is not as comfortable as is desirable. The construction makes the operation of attaching the tube end to the watchcase relatively difficult.

We have invented a tab stop for a watchband tube end which overcomes the defects of tube end structures of the prior art. Our arrangement prevents sharp corners of the band from extending beyond the watchcase when the band is off the wearer's wrist. It makes the watchband easier to don. Our tab end structure is simpler and less expensive to manufacture than are structures of the prior art intended to achieve the same purpose. A watchband incorporating our tab stop is more comfortable than are watchbands incorporating stop structures of the prior art. A tube end incorporating our tab stop is readily adaptable to watchcases requiring tab ends of different sizes. A tube end incorporating our tab stop is easier to assemble on a watchcase than is a tube end incorporating a stop structure of the prior art.

SUMMARY OF THE INVENTION

One object of our invention is to provide a tab stop for a watchband tube end which prevents the band from assuming a position in which sharp corners thereof extend above the watchcase.

Another object of our invention is to provide a tab stop for a watchband tube end which overcomes the defects of stop structures of the prior art.

A further object of our invention is to provide a tab stop for a watchband tube end which results in a more comfortable watchband than one provided with a stop structure of the prior art.

Still another object of our invention is to provide a tab stop for a watchband tube end which results in a tube end which can be adapted to watchcases of various sizes and which is easier to assemble on the watchcase than are tube ends provided with the stop construction of the prior art.

Other and further objects of our invention will appear from the following description.

In general our invention contemplates the provision of a tab stop for the tube end of a flexible, nonexpansible metal watchband in which a single, centrally located tab is secured to each of the spring pin-receiving tubes at the band ends so as to engage the underside of the watchcase when the watch is held face up to prevent the band from assuming a position at which sharp corners thereof extend above the case.

BRIEF DESCRIPTION OF THE DRAWINGS

In the accompanying drawings which form part of the instant specification and which are to be read in conjunction therewith and in which like reference numerals are used to indicate like parts in the various views:

FIG. 1 is a perspective view of the underside of a watchcase to which a band provided with our tube end stop lugs is secured.

FIG. 2 is an elevation of a watchcase and band assembly provided with our tube end stop tabs.

FIG. 3 is a fragmentary side elevation of a watchband provided with our tube end stop tab.

FIG. 4 is a side elevation of a watchcase and band assembly illustrating the problem solved by our construction.

FIG. 5 is a fragmentary sectional view of the watchband and case assembly shown in FIG. 4 taken along the line 5-5 of FIG. 4.

DESCRIPTION OF THE PREFERRED EMBODIMENT

Referring now to the drawings, a watchcase, indicated generally by the reference character 10, includes respective pairs of spaced, outwardly extending spring pin-receiving lugs or ears 12 and 14. One form of band which may be provided with our tube end stop tabs includes two halves 18 and 28, the end of each of which is cut to conform to the shape of the watchcase 10 which in the particular embodiment illustrated in the drawings is circular. As a result, there are formed two sharp corners 20 and 22. It will readily be appreciated that in other forms of bands for use with square or rectangular watchcases, the ends of the band half may be square but will have the same sharp corners 20 and 22. Moreover, when the band is of a type which is provided with a decorative adapter secured in any suitable manner to the end of the band, the adapter likewise has sharp corners similar to the corners 20 and 22.

A pair of spring pins 16 are provided for assembling the band halves 18 and 28 to the watchcase 10. We secure a pin-receiving tube 24 to the end of each of the band halves 18 and 28 by any suitable means. For example, a flange on the tube 24 may be soldered or brazed to the underside of the band adjacent the end. To secure the band halves to the case, a spring pin 16 is inserted in each of the tubes 24. The tube then is positioned between the lugs 12 and 14 and ends of the spring pin are inserted into holes (not shown) in the lugs.

In the condition of the parts just described, with the watchcase 10 held face up, as shown in FIG. 4, the band halves 18 and 28 drop under the influence of gravity to positions at which they extend generally vertically downwardly. In this position of the parts and in the absence of our stop tab construction, to be described, the sharp corners 20 and 22 are in positions wherein they may accidentally be struck by a person handling the assembly so that he may scratch or cut himself.

We secure a respective stop tab 26 to each of the tubes 24 at a location generally at the center of the tube. This may be accomplished in any suitable manner such, for example, as by soldering or brazing a small flange on the tab to the tube flange. In achieving this operation and before the band is adapted to the wrist of a particular wearer, we leave the tab 26 in the position indicated for the tab associated with the band half 18 in FIG. 2. The tab 26 is formed from any suitable sheet metal which will permit it to be bent to a desired position, such as that indicated for the tab 26 associated with the band half

28 in FIG. 2. In this way the tab can be bent to any position which will make the band most comfortable on the wrist of the wearer.

In operation of our tab stop, when the watch is removed from the wearer's wrist, the band halves 18 and 28 tend to drop downwardly so as to occupy a generally vertical position. As the band halves drop downwardly, tabs 26 engage the underside of the case 10 to prevent further movement of the band halves. As can be seen in FIG. 2, in this position of the band halves, the portions adjacent the watchcase extend generally horizontally outwardly and the sharp corners 20 and 22 are retained in the space between the lugs 12 and 14 so that they cannot project upwardly to positions at which they might cut a person handling the watch. Moreover, owing to the fact that they occupy this position, the relatively unattractive end of the band is substantially concealed from view. Since our tab is generally centrally located, the operation of removing the band half from the watchcase and that of replacing it are relatively simple since the ends of the spring pin are readily accessible. Owing to the fact that the tab is centrally located, it is not in a position in which it will engage the wearer's wrist when the watch is in use. Consequently, it will not discomfort the wearer.

It will be seen that we have accomplished the objects of our invention. We have provided a tab stop for a watchband end which prevents sharp corners of the band from being exposed when the watch is removed from the wearer's wrist. Our stop tab for a watchband tube end overcomes the disadvantages of tube end stop arrangements of the prior art. It is readily adapted to tube ends intended for a range of watchcase sizes. It does not interfere with the operation of assembling the band on the watchcase. It is simple and relatively inexpensive to

manufacture. A band incorporating our stop tab construction is more comfortable than is a band incorporating the stop structure of the prior art.

It will be understood that certain features and subcombinations are of utility and may be employed without reference to other features and subcombinations. This is contemplated by and is within the scope of our claims. It is further obvious that various changes may be made in details within the scope of our claims without departing from the spirit of our invention.

10 It is, therefore, to be understood that our invention is not to be limited to the specific details shown and described.

We claim:

1. A watchband for use with a watchcase having a curved outline configuration, said watchcase having pairs of spaced lugs including in combination, a first watchband portion formed of flexible metallic material, a second watchband portion formed of flexible metallic material, each of said watchband portions having an end with a curved configuration across the length of the portion, said end configuration being complementary to said curved outline configuration, said curved ends forming sharp corners at the edges of the band portions, means including respective pin-receiving tubes secured to the undersides of said band portions adjacent to but longitudinally spaced from said corners for mounting said band portions for swinging movement on said watchcase and single centrally located tabs carried by said tubes and extending inwardly under said watchcase to limit movement of said portion ends to positions at which said corners are below the upper surface of said watchcase.
- 15 2. A watchband as in claim 1 in which said tabs are formed of bendable material.
